UNITED STATES PATENT OFFICE.

HENRY A. ZIOLA, OF TOLEDO, OHIO, ASSIGNOR TO THE SWARTZBAUGH MANUFACTURING COMPANY, OF TOLEDO, OHIO, A CORPORATION.

HANDLE LATCH FOR DOORS.

Application filed March 11, 1927. Serial No. 174,568.

This invention relates to improvements in fastening devices especially adapted for use in conjunction with oven doors and the like and has as its primary object effectiveness of operation accompanied by ease in manipulation.

A more detailed object is the ready adjustment of the active parts for assuring a tight or substantially sealed joint between the door or cover and the oven or container at all times and regardless of wear.

With these and further objects in view, as will in part hereinafter become apparent and in part stated, the invention comprises certain novel structures, combinations and arrangements of parts as will subsequently be specified and therefore particularly pointed out in the accompanying claims.

In the accompanying drawings:

Fig. 1 is a perspective view of a fragment of an oven having an embodiment of the invention applied thereto, parts of the oven and its door being broken away and seen in section for disclosing structure otherwise concealed.

Fig. 2 is a top plan view thereof, the parts at one side being broken away and seen in section for disclosing parts beneath in elevation, the parts being seen on a reduced scale.

Fig. 3 is a vertical section taken approximately on the planes indicated by line 3—3 of Fig. 2, looking in the direction of the arrows.

Fig. 4 is a front elevation of the adjustable bracket plate detached, parts being seen on an enlarged scale.

Fig. 5 is a view in side elevation of the backing plate detached and observed from within its convex surface.

Fig. 6 is a transverse section taken on the planes indicated by line 6—6 of Fig. 5.

Referring to the drawings by numerals, 1 indicates an oven or like housing, made up of enclosing insulating walls of nested, spaced jackets or shells 2, 2, and appropriate insulating material, such as mineral wool therebetween. The oven housing is provided with an open end adapted to be closed by a door 3, preferably made up of a similarly insulating wall. In the detailed construction of the door 3, an outer covering plate 4, preferably of sheet metal, is employed and connected at its circumferential edges to an inner covering plate 5,

which is spaced from the plate 4 for heat insulating purposes, and the intervening area may be filled with appropriate heat insulating material, such as mineral wool or the like. Jackets 2 are connected at the end of the housing 1 by a transverse sheet or web 2' formed into a bordering rabbet or recessed seat 6 into which a substantial portion of the thickness of the door 3 is adapted to extend, as seen in Figs. 2 and 3. The outer wall of the rabbet or recessed seat 6 is formed by the meeting flange 2' of the transverse web 2' and the outer jacket 2, said flange and jacket being arranged in face contact and being fixed together, as by spot welding or otherwise, to form a longitudinally outstanding, bordering, terminal flange of housing 1.

The inner sheet 5 of the door 3 has its peripheral portion flanged outwardly at 8, and the sheet 4 of door 3 has its peripheral portion flanged inwardly to meet the flange 8, and the edges of the two sheets are folded together to form a seam 7, providing a bordering bead or abutment for abutting against the exposed edge of the flange formed of the meeting sheets 2 and 2'. That part of door 3 bounded by flange 8 is proportioned and located to meet and conform to the inner face of the flange 2' for enabling door 3 to be snugly seated in the rabbet 6 when in the closed position.

Door 3 is adapted to be removably seated in the rabbet 6 through the employment of any ordinary connecting means, such as the usual hinge connection or otherwise (not illustrated), and, when seated, is adapted to be fastened in the seated or closed position by the present improved latch and cooperating parts. To this end, the outstanding terminal flange of oven 1, formed in part from flange 2' is provided with apertures 9, 9, located to register with corresponding apertures 10, 10, formed in flange 8. Parts of the apertures 10 are preferably slightly outward of the apertures 9 so that a wedge inserted through the registering aperture is adapted and destined to tend to force the door 3 inward toward a more fully seated position in the rabbet 6. A divisional casing 11 is preferably arranged in the marginal portion of the door 3 about the place of the aperture 10 so as to leave an open or clearance space 12 for the free movement of wedging hooks 13, 13 carried by operating

levers 14, 14. There are as many hooks 13 and levers 14 as there are apertures 10, preferably two, and the levers 14 are connected by a clamping bolt 15 and spacing handle 16 to facilitate simultaneous manipulation of the levers 14. Levers 14 are pivoted on the same axis at 17, 17 to the outstanding ears 18, 18 of an adjustably mounted plate 19. The adjustable mounting of plate 19 is effected through the provision of slots 20, 20 formed in said plate and through which slots extend the retaining screws or bolts 21, 21. Some of the slots 20 may be accommodated by upwardly outstanding extensions or ears on the plate 19, or may be formed in the body of the plate according to the finished appearance desired. The plate 19 is arranged at the outer face of the outer sheet 4 of door 3, and a stiffening or anchoring plate 22 is arranged at the inner face of the sheet 4 and is of an area greater than the area of plate 9 to provide a supplemental back. For finish in appearance and adding to the stiffness of the sheet 4, the said sheet may be panelled or otherwise stamped or shaped up, as best seen in Fig. 3, and the plate 22 is given a contour to conform with such shaping of sheet 4. The plate 22 is preferably provided with an offset 23, and along its lower edge portion and above such offset, the plate is anchored to sheet 4 in any acceptable or appropriate manner, as by rivets 24, 24 extending through the sheet 4 and through apertures 25, 25 in plate 22. Obviously, spot welding or other means of connection may be used in lieu of the rivets. The plate 23 is formed with threaded apertures 26, 26 to receive the bolts 21, the inner end portion of each bolt 21 extending inward beyond the plate 22 and receiving a clamping or locking nut 27.

Plate 22 is provided with vertical slots 28 spaced longitudinally of the plate to correspond to the spacing of the rivets 14, each slot 28 registering with a corresponding slot 29 formed in and through the sheet 4 of drum 3. The levers 14 extend through the respective registering slots 28, 29, into the area 12 and carry the wedges 13, each of which upstands in hook-like shape and is provided with a tapering or wedge nose 13' and with an edge recess or notch 30 proportioned to receive the adjacent marginal portions of material surrounding the slots 9 and 10. Upward movement of wedges 13 is limited by the edges of levers 14 contacting with the upper extremities of slots 28, and the proper relative location of the wedges 13 is obtained by adjustment of the plate 19. Adjustment of plate 19 also enables the taking up of wear and insures a tight closure of the door 3, since wedges 13 may be thereby proportionally moved outward or in a direction away from the oven 1, whereby the wedging engagement of the tapering

ends 13' may be increased in tightness. Adjustment of plate 19 may be secured merely by loosening bolts 21, sliding the plate to the new location desired and tightening the bolts.

The upper edge portion of plate 22 is cut away at each end, as at 31, 31, leaving a relatively wide tongue 32 extending inward and sufficiently narrow to be accommodated between the wedges 13, the said tongue offering a stabilizing support to the outwardly turned marginal portions 8 of the sheet 5 which over-lie the upper portion of plate 22. The wedges 13 extend past the plate 22 in the spaces provided by the notches 31, 31.

Each lever 14 is preferably arcuate, as shown, but may be caused to assume any desired shape. The grip or handle 16 is preferably of heat insulated material but may be of any desired substance and is of sufficient weight, plus the extra length of levers 14 extended to pivots 17, to insure elevation of the wedges 13 by gravity under all normal conditions when the latch made up of the levers 14 and their connecting parts is released.

The preferred operation of the structure described consists, when the door 3 is closed, of grasping the handle 16 and elevating the same from the position seen in full lines in Figure 3 to the position shown in dotted lines therein. This action swings the inner ends of the levers 14 downward and withdraws wedges 13 from engagement through apertures 9 and 10. The operator then pulls on the handle 16 in a direction away from the oven 1, and the door 3 swings or otherwise moves away from the oven. When the door is to be closed, the handle 16 is elevated to the dotted line position of Fig. 3 and the door 3 is moved to the seated position, then the handle 16 is lowered, the lowering movement causing the tapered ends or noses 13' to pass through slots 10 and enter slots 9, engaging the outer terminus of said slots and wedging the parts for bringing the door 3 to a normal, seated position until the engaged walls of the slots enter the recesses 30 when the parts are latched closed by such engagement with said recesses.

Having thus described my invention, what I claim as new and desire to secure by Letters Patent of the United States, is:—

1. In mechanism of the class described the combination, with a door sheet, of a backing plate connected to the sheet at one face, a plate connected to the sheet at face opposite the first mentioned plate, said sheet and first mentioned plate being slotted, and a lever pivoted to said second mentioned plate and extending through the slot of the sheet and the first mentioned plate and carrying latching means at its inner portion.

2. In mechanism of the class described, the combination, with a door sheet, of a

backing plate connected to the sheet at one face, a plate connected to the sheet at the face opposite the first mentioned plate, said sheet and first mentioned plate being slotted, 5 and a lever pivoted to said second mentioned plate and extending through the slot of the sheet and the first mentioned plate and carrying latching means at its inner portion, the second mentioned plate being adjustably 10 connected to the sheet, to take up wear and to afford variability in the tightness with which the door may be shut,

3. In mechanism of the class described, the combination, with a container having a marginal rabbet and a closure adapted to be seated in said rabbet, the material of the closure and container at the place of the rabbet being formed with registering apertures when the closure is seated in the rabbet, a 20 lever pivoted to the closure, and a wedge carried by the lever in position to be swung through the registering apertures.

4. In mechanism of the class described, the combination, with a container having a marginal rabbet and a closure adapted to be seated in said rabbet, the material of the closure and container at the place of the rabbet being formed with registering apertures when the closure is seated in the rabbet, a 30 lever pivoted to the closure, and a wedge carried by the lever in position to be swung through the registering apertures, the wedge being formed with a locking notch.

5. In mechanism of the class described, the combination, with a container having a marginal rabbet and a closure adapted to be seated in said rabbet, the material of the closure and container at the place of the rabbet being formed with registering apertures 40 when the closure is seated in the rabbet, a lever pivoted to the closure, and a wedge carried by the lever in position to be swung through the registering apertures, the wedge being formed with a locking notch in its edge located to engage material bordering the registering slots for functioning as a detent against withdrawal of the wedge.

6. In mechanism of the class described, the combination with a container and a closure therefor, the container being formed with a rabbet for receiving the closure and the closure being adapted to be seated in the said rabbet, of a plate adjustably engaging the closure and having outstanding ears, a 50 pair of levers pivoted to the said ears and extending into the closure, the closure being slotted to accommodate the levers, a handle

connecting the outer portions of the levers, and hook wedges projecting from the inner portions of the levers, the rabbeted portion 60 of the container being apertured to receive said hook wedges.

7. In oven fastening apparatus, the combination, with the insulating wall of an oven and an insulated door cooperating therewith, of an adjustable plate engaging the outer portion of the door, a stiffening plate for the door inward of the adjustable plate, the door and stiffening plate being slotted, a locking lever pivoted to the adjustable plate and extending through the said slots, the stiffening plate being formed with an outstanding tongue operating with portions of the door for stabilizing the same, and latching means carried by the lever and 70 extending past said tongue, the oven being formed with means for receiving said latching means.

8. In fastening devices for insulated ovens, the combination of an insulated oven 80 wall having a rabbeted recess, and an insulated closure adapted to be seated in said recess, the closure comprising spaced inner and outer sheets, of a plate exterior of said outer sheet, a stiffening plate within the 85 outer sheet and connected thereto, means adjustably connecting the said first mentioned plate to the stiffening plate, a lever pivoted to the said first mentioned plate and extending through the outer sheet to the area between the sheets, and latching means extending from the lever between said plates in position for engaging the oven wall, said oven wall being formed with means for receiving said latching means. 95

9. In fastening devices for insulated ovens, the combination of an insulated oven wall having a rabbeted recess, and an insulated closure adapted to be seated in said recess, the closure comprising spaced inner and outer sheets, of a plate exterior of said outer sheet, a stiffening plate within the outer sheet and connected thereto, means adjustably connecting the said first mentioned plate to the stiffening plate, a lever pivoted to the said first mentioned plate and extending through the outer sheet to the area between the sheets, and a wedge extending from the free inner end portion of the lever and adapted to have locking engagement with the oven wall, the oven wall 100 being apertured to receive said wedge. 110

In testimony whereof I affix my signature.
HENRY A. ZIOLA.
